UNITED STATES PATENT OFFICE.

ALFRED H. DYSON, OF CHICAGO, ILLINOIS, ASSIGNOR TO MILO G. KELLOGG, OF CHICAGO, ILLINOIS.

TELEPHONE SYSTEM.

No. 830,981.

Specification of Letters Patent.

Patented Sept. 11, 1906.

Application filed April 17, 1905. Serial No. 266,063.

To all whom it may concern:

Be it known that I, ALFRED H. DYSON, a citizen of the United States, and a resident of Chicago, county of Cook, and State of Illinois, have invented certain new and useful improvements in Telephone Systems, of which the following is a specification.

My invention relates to telephone systems, and more specifically to providing apparatus for giving a special and auxiliary service in connection with such systems. The special service referred to consists in supplying means by which, from a substation a plurality of telephone-lines may be simultaneously connected to the line of the said substation, and means whereby the bells of all such lines may be simultaneously rung. Upon the response of the various subscribers they may be simultaneously given such information as may be desired. It is obvious that such an arrangement may be used for a variety of purposes. For instance, in a private system, such as a hotel system, in which the various rooms are connected with the office, my invention may be employed for the purpose of providing means for giving all the guests information at one and the same time in case of fire. Another case in which my invention may be advantageously employed is for the purpose of distributing news by telephone simultaneously to a number of offices from a central news-bureau. Another application would be the employment of my invention for the purpose of enabling the subscribers to an exchange to give information in case of fire simultaneously to the different engine-houses of a city fire department.

Figure 1, consisting of Sheets 1, 2, and 3, illustrates diagrammatically an application of my invention to an automatic telephone-exchange system. In the said Fig. 1 I have shown in addition to the apparatus specifically belonging to my invention apparatus adapted to be used in the ordinary course of exchange service; but I do not claim this latter by itself as my invention. In Fig. 2 I show a selective switch that may be employed in connection with my invention. Fig. 3 is a top view of the vertical magnet of said switch and its associated parts. Fig. 4 is a side view of the vertical magnet. Fig. 5 is a view in perspective of the side switch-pawl and its parts. Fig. 6 is a top view of

the rotary magnet and its parts. Fig. 7 shows a mechanism capable of being employed in connection with circuit D of Fig. 1. Fig. 8 shows an alternate mechanism for circuit D of Fig. 1.

Referring to Fig. 1, I show at A, in diagrammatic form, substation apparatus, including a pair of keys P and S, adapted to be used at will by the subscriber or attendant to ground at the substation limbs p and s of the telephone-line, respectively. At H, I have illustrated diagrammatically an automatic switch, ordinarily called a "first selector-switch," which, as shown, comprises the passive or immovable contact pieces or terminals 86, 87, and 88 and the active or movable contact-pieces or wipers 18, 19, and 20, together with a suitable organization of circuits and electromagnets to render said wipers controllable by means of keys P and S. At E, I have shown an automatic switch, ordinarily called a "second selector-switch," comprising passive contact-pieces 27, 28, and 29 and wipers 32, 33, and 34, together with an arrangement of electromagnets and circuits for controlling the movements of said wipers. At F, I have shown an automatic switch, ordinarily called a "connector-switch," provided with passive contact-pieces 35, 36, and 37 and wipers 44, 45, and 46, with a suitable organization of electromagnets and circuits for controlling the movements of the said wipers. At C, I have shown a second substation similar to that shown at A, and at G an automatic switch connected with the said substation by the two limbs of its telephone-line, the said switch comprising passive contact-pieces 47, 48, and 49 and wipers 89, 90, and 91, with circuits and electromagnets for controlling movements of the said wipers.

The above-described apparatus includes that necessary for establishing a connection between subscribers A and C in connection with the telephone system in association with which I have elected to describe my invention. The following is a brief description of the method of operation of the said system: Assuming that the number of subscriber C is "2345" and subscriber A desires connection with subscriber C, subscriber A first sends, by means of key P, two impulses of current from ground at the substation through relay 7 of first selector-switch H.

This causes a movement of wipers 18, 19, and 20 such as to bring them into a position ready to engage multiplied terminals of second selector-switches adapted to be used in establishing connection with a limited group of subscribers' lines, which is assumed to be a group of one thousand lines, including lines of subscribers to whom are assigned numbers from "2000" to "2999," inclusive. Adapted to be successively engaged by wipers 18, 19, and 20 are multiplied terminals of a plurality of such switches. Subscriber A now sends, by means of key S, one impulse of current from ground over limb *s* through relay 11 of switch H, which causes wipers 18, 19, and 20 to move into engagement with terminals of the first switch of the group above mentioned. In case the first switch is busy its terminal, corresponding to terminal 27 of switch E, will be grounded and wipers 18, 19, and 20 will be started upon a series of independent progressive movements over terminals of successive switches of the group until they rest in engagement with terminals of an idle switch, at which time the aforesaid movement ceases, owing to an absence of ground connection to its terminal corresponding to 27. Assuming this to occur when wipers 18, 19, and 20 engage terminals 27, 28, and 29 of second selector-switch E, subscriber A now sends a number of impulses, by means of key P, over limb *p* of the telephone-line, corresponding to the second digit of the called-subscriber's number, which in this case pass through contact 19 28 and through relay 30. The described three impulses of current operate to place wipers 32, 33, and 34 of switch E in a position ready to engage multiplied terminals of a plurality of connector-switches, each adapted to be used in establishing connection with a one-hundred-line group of subscribers' lines, to whom are assigned numbers from "2300" to "2399," inclusive. Subscriber A now sends, by means of key S, one impulse of current over limb *s* of the line, which in this case passes through relay 31, which operates to place wipers 32, 33, and 34 in engagement with terminals of the first connector-switch of the group above mentioned. In case such switch is busy an independent movement of wipers 32, 33, and 34 is caused in a manner similar to that before described, the movement of the wipers being arrested when they engage terminals of an idle connector-switch, assumed to occur when they engage, respectively, terminals 35, 36, and 37 of connector-switch F. Subscriber A now sends, by means of key P, four impulses of current from ground over limb *p* of the telephone-line, in this case passing through relay 38 of connector-switch F, which impulses operate to place wipers 44, 45, and 46 in a position such that they are ready to be caused to move over terminals of

a group of subscribers' lines, to whom are assigned numbers from "2341" to "2350," inclusive. Subscriber A now sends, by means of key S, one impulse of current over limb *s* of the telephone-line, which in this case passes through relay 39, operating to place wipers 44, 45, and 46 under control of a second set of impulses to be sent through relay 38. Subscriber A now sends, by means of key P, five impulses of current over limb *p* of the line, passing through relay 38, which causes wipers 44, 45, and 46 to move over terminals of successive subscribers' lines until they reach terminals of the line of subscriber 2345 or subscriber C. In case this line is already in use contact-piece 47 will be grounded, and when subscriber A, by means of key S, sends one impulse of current over limb *s* through relay 39, as he now proceeds to do, wipers 44, 45, and 46 disengage contact-pieces 47, 48, and 49, respectively, and return to normal. Subscriber A now sends, by means of key P, an impulse of current over limb *p*, which passes through relay 38 and in this case operates to cut busy back machine 43 into circuit with the line of subscriber A and causes him to receive the usual busy-signal by means of his receiver. In case the line of subscriber C is not busy wipers 44, 45, and 46 rest in engagement with contact-pieces 47, 48, and 49, and the impulse of current last described as being sent by subscriber A, by means of key P, causes the energization of relay 42, operating to cut ringing-generator 92 into circuit with the line of the called subscriber, causing his bell to ring and notifying him that his attention is desired. When subscriber A releases key P, relay 42 is de-energized and the talking-circuit of the lines established. When the subscribers have finished their conversation, they replace their receivers and respectively send, by means of keys P and S, simultaneous impulses of current from ground over their respective telephone-lines. In case the called subscriber C does this first connector-switch F returns to normal, and when subscriber A does so switches H and E return to normal. In case subscriber A sends the aforementioned simultaneous impulses of current before subscriber C switches F, E, and H all return to normal.

Generally speaking, the automatic telephone system illustrated may be said to operate as follows: The subscriber desiring to make a call operates a first selector-switch to pick out a desired one-thousand-line group of subscribers represented by second selector-switches. He then operates a second selector-switch to pick out a one-hundred-line group, represented by connector-switches, of subscribers from the thousand-line group, among which is the line of the desired subscriber. He then operates a

connector-switch to pick out from the one-hundred-line group the individual line desired.

The mechanism of a switch, such as diagrammatically shown at H, E, F, and G, may conveniently be constructed to comprise a shaft upon which the wipers are rigidly mounted, the energizing impulses sent by the subscriber over limb *p* in making a call causing successive vertical movements of the shaft to bring the wipers into juxtaposition with different horizontal curved rows or levels of terminal contact-pieces. The independent progressive movements of selector-switches, referred to in the foregoing description as started by impulses of current sent over limb *s* of the telephone-line, may be effected by imparting a rotary motion to the shaft, which may be axially disposed with respect to the various horizontal rows of contacts. In the case of connector-switch F this rotary motion is of course not of an independent character, but is controlled by a series of impulses sent over limb *p* of the line.

Having described, in a general way, the operation of the telephone system in connection with which I show the special-service system, I will now describe in detail the circuit arrangement and method of operation of the latter.

In Fig. 1, B and C may be regarded as substations located in two different engine-houses of a fire-department. The substation illustrated at C is shown connected by the two limbs of its telephone-line with contact-pieces 48 and 49 of a first selector-switch G at the central office, the arrangement being such that calls may be made and received by the substation in the ordinary course of business in a manner similar to that described in the foregoing. The substation illustrated at B is connected by the two limbs of its telephone-line with contact-pieces 93 and 94 of a switch at the central office, which may be similar to that shown at G, the passive contact-pieces 92, 93, and 94 of this switch alone being shown in the illustration. Conductors are provided leading from contact-pieces 47, 48, and 49 of the switch of substation C to the switching mechanism of relay 72, terminating thereat in anvils 77, 75, and 78, respectively. Similar conductors are provided leading from contact-pieces 92, 93, and 94 of the switch of substation B to the switching mechanism of relay 72^a, terminating thereat in anvils 77^a, 75^a, and 78^a. Referring now to D, I there show a switching device including passive contact-pieces 98, 21, and 22 and active terminals 66, 68, and 70, together with a suitable organization of circuits for operating the special-service system of my invention. Contact-pieces 98, 21, and 22 are adapted to be engaged by wipers 18, 19, and 20 under control of the substation switching apparatus shown at

A. The said contact-pieces 98, 21, and 22 are preferably located upon a level individual to themselves and are preferably the only contact-pieces upon that level and so placed that the first rotary movement of the shaft 70 will bring the wipers of the selector-switch into engagement with them. Assuming that the said contact-pieces 98, 21, and 22 are placed upon the ninth level, so that nine vertical step-by-step movements are to be 75 imparted to shaft 80 of first selector-switch H to bring wipers 18, 19, and 20 into a position such that upon a rotary movement of the shaft they will engage said contact-pieces, and that subscriber A desires to employ the special-service arrangement, the operation of the system is as follows: Subscriber A depresses and releases key P nine times, thus establishing nine temporary ground connections to limb *p* of the line at the 85 substation and sending nine impulses of current over the said limb by the following path: from ground, over limb *p*, through arm *a*², through the winding of relay 7 to battery 17, causing nine energizations and deenergizations of the said relay. The resulting attractions and releases of the relay's armature cause nine impulses of current to flow over the following path: from ground, through contact between springs 9 and 8, 95 through contact 13 15, through the winding of magnet 16 to battery 17, resulting in nine energizations and deenergizations of magnet 16. Magnet 16, by mechanical connections, (not shown,) thereby is caused to 100 effect nine vertical step-by-step movements of shaft 80, bringing wipers 18, 19, and 20 to positions horizontal with contact-pieces 98, 21, and 22. Subscriber A now depresses and releases key S a single time, causing one impulse of current to flow from ground at the 105 substation, over limb *s* of the line, through arm *a*³, through the winding of relay 11 to battery 17, energizing and deenergizing the said relay and causing the attraction and release of its armature. An impulse of current is thereby caused to flow over the following path: from ground, through contact between springs 9 and 10, through the winding of relay 12 to battery 17, energizing and de 110 energizing the said magnet. By mechanical means (not shown) the consequent attraction and release of the armature of relay 12 effects the following circuit changes: arms *a*, *a*¹, *a*², and *a*³ are moved into engagement 115 with contact-points *b*, *b*¹, *b*², and *b*³, respectively. The engagement of arm *a* with contact-point *b* establishes a path for the flow of current from ground, through contact *a* *b*, through magnet 23 to battery 120 26, causing the energization of magnet 23, which thereupon attracts its armature, breaking its own energizing-circuit. The energization described of magnet 23 by mechanical means (not shown) effects a rotary 125 30

4

movement of shaft 80, so that wipers 18, 19, and 20 engage contact-pieces 98, 21, and 22 of switch D. The energization and deenergization of magnet 23, just described, also operated to effect the following circuit changes: Arms a , a' , a^2 , and a^3 are moved into engagement with contact-points c , c' , c^2 , and c^3 by mechanical means. (Not shown in the illustration.) Subscriber A now depresses key P and releases it, which act operates to establish a talking-circuit from his line through to substations B and C in the following manner: The depression of key P establishes a path for the flow of current from ground at the substation over limb p of the line, through contact a^2 c^2 , through contact 19 21, through relay 50 to battery 57, energizing the said relay. This energization attracts the relay's armature and establishes a path for the flow of current as follows: from ground at switch D, through contact between springs 55 and 54, through contact between springs 52 and 51, a portion of the current then flowing through relay 81 to battery 57, causing the energization of the said relay. The deenergization of said relay upon the release of key P by mechanical means (not shown) moves active terminals 66, 68, and 70 into engagement with contact-points 67, 69, and 71, respectively. A portion of the described flow of current also passed through the winding of relay 64 to battery 57, energizing the said relay and causing the attraction of its armatures. The generator-circuit was at that time open at contacts 68 and 70. The engagement of active terminal 66 with contact-point 67 established a path for the flow of current from ground, through contact 66 67, over conductor 83, the said current passing in parallel through the windings of relays 72 and 72^a to battery 73, causing the energizations of the said relays. It is apparent that these relays will continue energized until terminal 66 disengages contact-point 67, as hereinafter described. The energization of relays 72 and 72^a caused the attraction of their armatures, the resulting closing of contacts 76 77 of relay 72 and 76^a 77^a of relay 72^a connecting contact-pieces 47 and 92 to ground and rendering the lines of stations C and B busy with respect to incoming calls in the regular course of business. The energization of relays 72 and 72^a also resulted in bridging the lines of substations C and B across conductors 84 and 85. Subscriber A again depresses key P, resulting in a flow of current through relay 64, as before described, this time cutting ringing-generator 65 into circuit with conductors 84 and 85, ringing-current therefrom passing through the bells of the two substations C and B. When subscriber A releases key P, circuit is broken through relay 64, deenergizing the said relay. Its armatures return to their normal positions, (shown in the illustrations,) establishing the talking-circuit and cutting generator 65 out of circuit with conductors 84 and 85. When the call is responded to at substations C and B, subscriber A is able to simultaneously give such information as he desires to the persons who answer the call at substations C and B, the conversational circuit being traced from substation A, over limb p of the line, through contact a^2 c^2 , contact 19 21, through condenser m , through contact 68 69, over conductor 84, over the telephone-lines of substations C and B in parallel, returning over conductor 85, through contact 71 70, through condenser m' , through contact 22 20, through contact c^3 a^3 , over limb s of the line and through substation A. Having given the desired information, subscriber A simultaneously depresses keys P and S and releases them, thus grounding simultaneously limbs p and s of his telephone-line. Current is thereby caused to flow from ground, over limb p of the line, through contact 19 21, through relay 50 to battery 57, and from ground at the substation over limb s of the line, through contact 20 22, through relay 56 to battery 57. Relays 50 and 56 are thereby energized, establishing a path for the flow of current as follows: from ground at switch D, through contact between springs 55 and 53, through the winding of magnet 58 to battery 57. This flow of current energizes magnet 58, attracting its armature 95, causing a flow of current from battery 57, through resistance 97, contact 98 18, relay 25, contact a' c' to ground. Relay 25 attracts its armature, causing a current-flow from ground, through magnet 24 to battery 26, energizing magnet 24. When subscriber A releases the keys at his substation, circuit is broken by the resulting deenergization of relay 56 through magnet 58, and its deenergization by mechanical means (not shown) causes active terminals 66, 68, and 70 to disengage, respectively, contact-points 67, 69, and 71, returning to their normal positions, as illustrated. The disengagement of terminal 66 from contact-point 67 opens circuit through relays 72 and 72^a, deenergizing them, allowing the return of their armatures to normal, thus breaking the bridges of the line of subscribers C and B to conductors 84 and 85 and also removing ground from contact-points 47 and 92, associated with the lines of substations C and B, whereby the said lines will no longer test "busy" to incoming calls. The deenergization of magnet 58 causes the deenergization of relay 25, and this in turn causes the deenergization of magnet 24. The deenergization of magnet 24 by mechanical means (not shown) causes wipers 18, 19, and 20 to disengage contact-pieces 98, 21, and 22 and return to normal. While the grounding of both limbs of his line by subscriber A is not essential to the release described, it is essential in regular 130

service operations and would in practice be done, and I have therefore so described the operation.

The special-service circuit also provides means whereby after subscriber A has conveyed the desired information the release of the line of the called substations may be secured by switching operations formed at one of the called substations. Assuming that this is to be done from substation C, the operation is as follows: By means of keys P and S the two limbs of the telephone-line of substation C are simultaneously grounded. This places a ground on conductor 84 through contact 75 74 and on conductor 85 through contact 78 79. Current is thereby caused to flow from ground at substation C, over conductor 84, through contact 69 68, through relay 59 to battery 57, and over conductor 85, through contact 71 70, through relay 60 to battery 57. These flows of current cause a simultaneous energization of relays 59 and 60, attracting their armatures and causing a flow of current over the following path: from ground at switch D, through springs 63 62 61, through the winding of magnet 58 and to battery 57. When the keys at substation C are released, relays 59 and 60 are deenergized and the return of their armatures to normal opens circuit through magnet 58, deenergizing the said magnet and causing the return by mechanical means (not shown) of active terminals 66, 68, and 70 to their normal positions and also of wipers 18, 19, and 20. Should contact-piece 98 be omitted from the switch D, means would still be provided, operable either by the calling subscriber or by any one of the called stations, for releasing the said called stations and returning them to their normal or idle-circuit conditions; but it would be impossible to automatically disconnect switch H from switch D, as described above, and under these conditions this would have to be done by an attendant at the central office. I consider this latter in some respects a desirable method of operation in connection with the fire-alarm service I have described, as in case an alarm should be given of an improper or mischievous nature the latter method of operation would enable the source of such alarm to be traced, while knowledge that means are provided for this purpose will act as a deterrent to persons who might otherwise give such alarms.

The terminals 98, 21, and 22 of the special-service circuit may be multiplied throughout the switches of the exchange in such a manner as to enable each subscriber to obtain connection with and operate the special-service circuit, substations such as C and B, whose lines are thrown together upon the operation of the special-service circuit, being able to do this also.

The multiplying of the terminals of the special-service switch may be done in a va-

riety of ways, and the operation of the special-service circuit may be restricted to certain substations only by omitting multiples of the circuit's terminals, as desired. Should it be so desired, it may thus be arranged that only 70 substations whose lines are adapted to be thrown together by the operation of the special-service circuit are enabled to throw the lines together in the manner described. My invention is susceptible to widely-varying arrangements and is not to be limited in this respect.

It is to be understood that the terminals of the special-service switch need not be associated with wipers of first selector-switches, 80 but may, if desired, be associated with wipers of second selector-switches or connector-switches. The aforementioned and other modifications may be readily made without departing from the substance of my invention, 85 which is of general application, and I desire not to be limited to the particular arrangements shown.

While I have shown a plurality of batteries in Fig. 1, it is to be understood that they may 90 be one and the same battery.

In practice a substation calling device not requiring by the subscriber the amount of care involved by the use of the simple keys P and S would be provided.

Having described the circuit structure of my invention, I will now refer to the mechanical drawings, illustrative of certain mechanism that may conveniently be used in connection with my invention. Any suitable form 100 of mechanical switch may be employed in connection with the circuits shown at H, E, F, and G, that shown in Fig. 2 being a diagrammatic representation of a switch in extensive commercial use in the United States. 105 For convenience of reference I have supplied characters to Fig. 2 corresponding to those of circuit H, although the switch shown in said Fig. 2 is generic to and equally adapted to be operated in connection with circuits E 110 and G and with the omission of arm 23^a for circuit F. In said Fig. 2 shaft 80 has fastened to it wipers 18, 19, and 20, adapted to be raised and rotated with the shaft, which is journaled to the supports of contact-banks L 115 and 1. For securing these movements of the shaft the vertical magnet 16, with its armature-actuated pawl 16^c, is provided, the pawl being arranged to engage the horizontal teeth of the ratchet shown fastened to the shaft 80. 120 With the first energization of magnet 16 pawl 16^c raises the shaft a step and lugs 16^a and 16^b of the armature of magnet 16 release, respectively, double dog d d, which engages with its upper portion a horizontal tooth of the shaft-ratchet to prevent back movement, and arm 12^e from its interlocking relation with the pin on the armature of the release-magnet 24, which renders side-switch pawl 12^a capable of movement, as hereinafter in- 130

- dicated.) Successive thrusts of pawl 16^c raise shaft 80 successive steps to bring wipers 18, 19, and 20 horizontal with successive levels of contacts of their respective banks.
- 5 When the desired number of vertical steps has been imparted to the shaft, the side-switch magnet 12 is energized and deenergized, which by the attraction of its armature causes the end of pivoted pawl 12^a to engage tooth 12^b and on the release of the armature allows the said pawl to slip down into engagement with tooth 12^c under the influence of the associated spiral spring. Arm a, fastened to pawl 12^a, is thereby caused to move off its normal contact to engage contact b. In Fig. 5 is indicated the manner in which each movement of pawl 12^a effects a plurality of simultaneous circuit changes. Rotary movements of shaft 80, causing the engagement of wipers 18, 19, and 20 with the contacts of selected levels of their banks, is accomplished by thrusts of pawl 23^b, fastened to the armature of rotary magnet 23. Each time magnet 23 is energized a thrust of the pawl is caused, which engages the teeth of the vertically-disposed ratchet of the shaft successively, the lower portion of double dog d d engaging successive teeth of the ratchet and preventing back movement. The shaft 80 is thus rotated, each rotary step causing wipers 18, 19, and 20 to engage successive contact sets of selected levels. The arm 23^a is provided for the selector-switches only (being omitted in the connector-switches) and is adapted to 35 thrust the armature of side-switch magnet 12 to the right when magnet 23 is energized, allowing the said armature to be retracted when magnet 23 is deenergized. The described movement of the armature of side-switch magnet 12 causes pawl 12^a to advance to engage tooth 12^c, thereby placing arms a a', a², &c., in engagement with their third contacts c c', c², &c. This is the method of operation hereinbefore referred to as causing arms 45 a, a', a², and a³ to engage contact-points c, c', c², and c³ at the time when wipers 18, 19, and 20 engaged contacts 98, 21, and 22, the said contacts being assumed to be the first and only connected contacts of the ninth levels.
- 50 In regular-service operations the function of arm 23^a is to cause the side-switch arms to engage their third contacts when the first trunk of the selected group is idle. If this trunk is busy, side-switch magnet 12 becomes energized as arm 23^a completes its stroke and holds the armature attracted, thus preventing movement of the side-switch pawl 12^a until an idle trunk is reached by the wipers, when magnet 12 becomes deenergized.
- 55 comes energized as arm 23^a completes its stroke and holds the armature attracted, thus preventing movement of the side-switch pawl 12^a until an idle trunk is reached by the wipers, when magnet 12 becomes deenergized.
- 60 and pawl 12^a moves to engage tooth 12^c. To restore the switch to normal, release-magnet 24 is energized and deenergized, whereby its armature is attracted and then retracted. When attracted, it moves pivoted arm 24^a to 65 the left to engage with its hook the pin upon double detent d d, while the pin upon the armature engages the offset of arm 12^c. When the armature of magnet 24 is now retracted, it moves arm 12^c to the right, resetting pawl 12^a in engagement with tooth 12^c to restore arms a a', a², &c., while arm 24^a simultaneously withdraws the double detent d d from engagement with the shaft-ratchets, leaving the shaft free to be rotated by spring 80^a (against whose torsion it was turned) until 75 wipers 18, 19, and 20 pass to the left of banks L and 1, when the shaft is free to descend to normal under the influence of gravity, assisted by spring 80^a.
- In Fig. 7 I show an adaptation of the side-switch operating and restoring mechanism of Fig. 2 arranged for employment in connection with circuit D. Like parts of circuit D and Fig. 7 have corresponding characters. Referring to Fig. 7, when, as hereinbefore described, magnet 81 is energized its attracted armature moves arm 81^a downwardly, whose pivoted arm 81^c withdraws arm 58^a from engagement with pin 81^f on side switch pawl 81^a, thus terminating the normal locked condition 85 of said pawl, so that with the ensuing deenergization of magnet 81 and the consequent retraction of its armature the said pawl moves to engage tooth 81^c, carrying switch-arms 66, 68, and 70, fastened to the pawl, into engagement with their respective contacts 67, 69, and 71. When now magnet 58 attracts its armature, arm 58^a is moved to the left, so that the offset at its extremity engages pin 81^f upon pawl 81^a. When magnet 58 is 90 thereupon deenergized, its retracted armature moves arm 58^a to the right, which, continuing in engagement with pin 81^f, moves pawl 81^a to again engage tooth 81^c, the pawl in its return movement carrying switch-arms 66, 95 68, and 70 out of engagement with contacts 67, 69, and 71 and to their normal positions, as shown in Fig. 7. Another arrangement of mechanism adapted for use in connection with circuit D is shown in Fig. 8. Here magnet 81 is provided with a single-hooked spring 81^b, fastened to its armature. When 100 81 is energized, the attraction of its armature draws spring 81^b down to release pawl 81^a, which is thereupon moved, as usual, by its associated spiral spring, causing switch-arm 66 to engage contact 67. Arm 58^c, pivoted to pawl 81^a, having an orifice fitting over pin 58^b of the armature of magnet 58, limits the movement of the pawl. When magnet 58 is 105 energized, its attracted armature, acting by means of pin 58^b upon arm 58^c, causes pawl 81^a to again slip into a position where it is held by toothed spring 81^b, arm 66 being simultaneously returned to normal.
- In the employment of the structure of Fig. 8 the depression of key P after switch H has selected switch D moves arms 66, 68, and 70 to engage their alternate contacts, and if key P is kept depressed ringing-current is immediate 110

dately thereafter projected over the special-service lines.

Having shown a preferred embodiment of my invention, I shall claim the same broadly, it being my intention not to limit myself in the broad claims to the particular embodiment herein particularly set forth, including the combination of my invention with an automatic telephone system.

10. I claim—

1. In an electrical exchange system, a plurality of lines connecting substations with the exchange, apparatus for each line at the exchange for regular service, a line connecting a calling-substation with the exchange, a special-service circuit associated with said plurality of lines at the exchange, means for operating said circuit from the calling-substation to switch said plurality of lines into a common electrical circuit with said line and means for electrically transmitting intelligence over said common circuit when established.

2. In an electrical exchange system, a plurality of lines connecting substations with the exchange, apparatus for each line at the exchange for regular service, a line connecting a calling-substation with the exchange, a special-service circuit associated with said plurality of lines at the exchange, means for operating said circuit from the calling-substation to switch said plurality of lines into a common electrical circuit with said line, means for electrically transmitting intelligence over said common circuit when established and means, operable from any substation included therein, for destroying such common circuit.

3. In a telephone-exchange system, a plurality of telephone-lines connecting substations with the exchange and provided with line-circuits for regular exchange service thereat, a telephone-line connecting a calling-substation with the exchange, and a special-service circuit at the exchange associated with said plurality of lines, adapted to be operated from said calling-substation to switch said plurality of lines into a common conversational circuit including the line of the calling subscriber.

4. In a telephone-exchange system, a plurality of telephone-lines connecting substations with the exchange and provided with line-circuits for regular exchange service thereat, a telephone-line connecting a calling-substation with the exchange, a special-service circuit at the exchange associated with said plurality of lines, adapted to be operated from said calling-substation to switch said plurality of lines into a common conversational circuit including the line of the calling subscriber, means controlled from the calling-substation for ringing the substations of said plurality of lines when so switched and apparatus operable from any substation in-

cluded in said conversational circuit adapted to destroy such circuit.

5. In a telephone-exchange system, a plurality of telephone-lines connecting substations with the exchange, a line-circuit for each line at the exchange, a special-service circuit at the exchange, a relay for each of said lines associated with said special-service circuit, and branches extending from said lines to said relays, a telephone-line connecting a calling-substation with the exchange, and apparatus associated with said line at the exchange adapted, under substation control, to operate said relays to switch said plurality of lines into a common conversational circuit including the line of said calling-substation.

6. In a telephone-exchange system, a plurality of telephone-lines connecting substations with the exchange, a line-circuit for each line at the exchange, a special-service circuit at the exchange, a relay for each of said lines associated with said special-service circuit, and branches extending from said lines to said relays, a telephone-line connecting a calling-substation with the exchange, apparatus associated with said line at the exchange adapted, under substation control, to operate said relays to switch said plurality of lines into a common conversational circuit including the line of said calling-substation, and apparatus operable from a substation included in said conversational circuit adapted to destroy such circuit.

7. In an automatic telephone-exchange system, the combination of a plurality of telephone-lines connecting substations with the exchange, an automatic switch for each of said lines at the exchange for ordinary service, a special-service circuit at the exchange, relays associated with said circuit, one for each of said lines, and branches extending from each line to its respective relay, a telephone-line connecting a calling-substation with the exchange, calling mechanism for said line at the substation, an automatic switch at the exchange adapted, in response to said calling mechanism, to connect said line with said special-service circuit, a central source of current, apparatus included in said circuit adapted, responsive to said calling mechanism, to switch said source in circuit with, and energize, said relays, and switching mechanism for said relays adapted, in response to their energization, to include their respective lines in a common conversational circuit with said calling-subscriber's line.

8. In an automatic telephone-exchange system, the combination of a plurality of telephone-lines connecting substations with the exchange, an automatic switch for each of said lines at the exchange for ordinary service, a special-service circuit at the exchange, relays associated with said circuit, one for

each of said lines, and branches extending from each line to its respective relay, a telephone-line connecting a calling-substation with the exchange; calling mechanism for said line at the substation, an automatic switch at the exchange adapted, in response to said calling mechanism, to connect said line with said special-service circuit, a central source of current, apparatus included in said circuit adapted, responsive to said calling mechanism, to switch said source in circuit with, and energize, said relays, switching mechanism for said relays adapted, in response to their energization, to include their respective lines in a common conversational circuit with said calling-subscriber's line, and apparatus adapted, under control of the calling-substation, to simultaneously signal the substations of said plurality of lines when so included.

9. In an automatic telephone-exchange system, the combination of a plurality of telephone-lines connecting substations with the exchange, an automatic switch for each of said lines at the exchange for ordinary service, a special-service circuit at the exchange, relays associated with said circuit, one for each of said lines, and branches extending from each line to its respective relay, a telephone-line connecting a calling-substation with the exchange, calling mechanism for said line at the substation, an automatic switch at the exchange adapted, in response to said calling mechanism, to connect said line with said special-service circuit, a central source of current, apparatus included in said circuit adapted, responsive to said calling mechanism, to switch said source in circuit with, and energize, said relays, switching mechanism for said relays adapted, in response to their energization, to include their respective lines in a common conversational circuit with said calling-subscriber's line, apparatus adapted, under control of the calling-substation, to simultaneously signal the substations of said plurality of lines when so included and apparatus adapted to be operated, under control of the calling-substation, to disconnect the line of said substation from said special-service circuit and return said circuit to normal.

10. In a telephone-exchange system, a plurality of telephone-lines connecting substations with the exchange and provided with line-circuits for regular exchange service thereat, additional telephone-lines connecting substations with the exchange and provided with line-circuits for regular exchange service thereat and a special-service circuit at the exchange associated with said plurality of lines adapted to be operated from any substation to switch said plurality of lines into a common conversational circuit including the line of the operating-substation

11. In a telephone-exchange system, a plurality of telephone-lines connecting substations with the exchange and provided with line-circuits for regular exchange service thereat, additional telephone-lines connecting substations with the exchange and provided with line-circuits for regular exchange service thereat, a special-service circuit at the exchange associated with said plurality of lines adapted to be operated from any substation to switch said plurality of lines into a common conversational circuit including the line of the operating-substation, and apparatus operable from any substation included in said common circuit adapted to destroy such circuit.

12. In a telephone-exchange system, a plurality of telephone-lines connecting substations with the exchange and provided with line-circuits for regular exchange service thereat, additional telephone-lines connecting substations with the exchange and provided with line-circuits for regular exchange service thereat, a special-service circuit at the exchange associated with said plurality of lines adapted to be operated from any substation to switch said plurality of lines into a common conversational circuit including the line of the operating-substation, mechanism controllable from the operating-substation, adapted to ring the substations of said plurality of lines, when so switched, and apparatus operable from any substation included in said common circuit adapted to destroy such circuit.

13. In a telephone-exchange system, a plurality of telephone-lines connecting substations with the exchange, additional telephone-lines connecting substations with the exchange, a line-circuit for each line at the exchange for regular service, a special-service circuit at the exchange, a relay for each of said plurality of lines associated with said special-service circuit, and branches extending from said lines to said relays, and apparatus for operating said relays, adapted to be controlled from any substation, to switch said plurality of lines into a common conversational circuit including the line of the controlling-substation.

14. In a telephone-exchange system, a plurality of telephone-lines connecting substations with the exchange, additional telephone-lines connecting substations with the exchange, a line-circuit for each line at the exchange for regular service, a special-service circuit at the exchange, a relay for each of said plurality of lines associated with said special-service circuit, and branches extending from said lines to said relays, apparatus for operating said relays, adapted to be controlled from any substation, to switch said plurality of lines into a common conversational circuit including the line of the con-

trolling-substation, and apparatus operable from a substation included in said common circuit adapted to destroy such circuit.

15. In a telephone-exchange system, a plurality of telephone-lines connecting substations with the exchange, additional telephone-lines connecting substations with the exchange, a line-circuit for each line at the exchange for regular service, a special-service circuit at the exchange, a relay for each of said plurality of lines associated with said special-service circuit, and branches extending from said lines to said relays, apparatus for operating said relays, adapted to be controlled from any substation, to switch said plurality of lines into a common conversational circuit including the line of the controlling - substation, mechanism, operable from the controlling-substation, adapted to ring the substations of said plurality of lines when so switched, and apparatus operable from a substation included in said common circuit adapted to destroy such circuit.

16. In an automatic telephone-exchange system, a plurality of telephone-lines connecting substations with the exchange, a special-service circuit at the exchange, relays associated with said circuit, one for each of said lines, and branches extending from each line to its respective relay, additional telephone-lines connecting substations with the exchange, calling mechanism for each line at its substation, automatic switches at the exchange responsive to said calling mechanism for regular service and for connecting any line with said special-service circuit, and apparatus included in said circuit adapted, when a line is connected therewith, to switch said plurality of lines into a common conversational circuit including the connected line.

17. In an automatic telephone-exchange system, a plurality of telephone-lines connecting substations with the exchange, a special-service circuit at the exchange, relays associated with said circuit, one for each of said lines, and branches extending from each line to its respective relay, additional telephone-lines connecting substations with the exchange, calling mechanism for each line at its substation, automatic switches at the exchange responsive to said calling mechanism for regular service and for connecting any line with said special-service circuit, apparatus included in said circuit adapted, when a line is connected therewith, to switch said plurality of lines into a common conversational circuit including the connected line, and apparatus operable from any substation included in said common circuit adapted to destroy such circuit.

18. In a telephone-exchange system, a plurality of telephone-lines connecting substations with the exchange, a regular-service line-circuit for each line at the exchange

and a special-service circuit at the exchange adapted to be operated from a substation of said plurality to switch said lines into a common conversational circuit.

19. In a telephone-exchange system, a plurality of telephone-lines connecting substations with the exchange, a regular-service line-circuit for each line at the exchange, a special-service circuit at the exchange adapted to be operated from a substation of said plurality to switch said lines into a common conversational circuit and apparatus operable from a substation included in such common circuit to destroy the said circuit.

20. In a telephone-exchange system, a plurality of telephone-lines connecting substations with the exchange, apparatus at the exchange for connecting any two of said lines into an individualized conversational circuit, a special-service circuit at the exchange, a relay for each line associated with said special-service circuit, and branches extending from each line to its respective relay, and apparatus, adapted to be controlled from any of said substations, for operating said relays to switch said plurality of lines into a common conversational circuit.

21. In a telephone-exchange system, a plurality of telephone-lines connecting substations with the exchange, apparatus at the exchange for connecting any two of said lines into an individualized conversational circuit, a special-service circuit at the exchange, a relay for each line associated with said special-service circuit, and branches extending from each line to its respective relay, apparatus, adapted to be controlled from any of said substations, for operating said relays to switch said plurality of lines into a common conversational circuit and mechanism adapted to be operated from any substation included in said common circuit to destroy such circuit.

22. In an automatic telephone-exchange system, a plurality of telephone-lines connecting substations with the exchange, calling mechanism for each line at its substation, automatic switches at the exchange responsive to said mechanism, adapted to connect said lines into individualized conversational circuits, a special-service circuit at the exchange, relays associated with said circuit, one for each of said lines, and branches extending from each line to its respective relay, and mechanism included in said switches adapted to enable any substation of said plurality of lines to control said circuit and operate said relays to switch said lines into a common conversational circuit.

23. In an automatic telephone-exchange system, a plurality of telephone-lines connecting substations with the exchange, calling mechanism for each line at its substation, automatic switches at the exchange responsive to said mechanism, adapted to connect

- 5 said lines into individualized conversational circuits, a special-service circuit at the exchange, relays associated with said circuit, one for each of said lines, and branches extending from each line to its respective relay, mechanism included in said switches adapted to enable any substation of said plurality of lines to control said circuit and operate said relays to switch said lines into a common conversational circuit, and apparatus operable from any substation included in said common circuit to destroy such circuit.
- 10 24. A telephone system including telephone-lines extending from substations to the exchange, a telephone-switchboard, a special-service circuit at the exchange, branches extending therefrom to certain telephone-lines, means at a substation for transmitting distinctive signals over its associated line to operate said special-service circuit, and mechanism included therein adapted when said circuit is so operated to connect said lines into a common circuit.
- 15 25. A telephone system including substations, telephone-lines connecting said stations to a telephone-switchboard, means for transmitting signals over said lines for ordinary telephone service, branches extending from telephone-lines to switching mechanisms of 20 relays individual to them, and means for transmitting distinctive signals from a substation to cause the operation of said relays to switch said lines into a common circuit including the line of said substation.
- 25 30. 26. A telephone-exchange system including telephone-lines connecting substations with the exchange, terminals for said lines, apparatus for connecting therewith in the regular course of exchange service, additional terminals for said lines, a special-service circuit, means for transmitting distinctive signals over calling-lines to cause the operation of said special-service circuit to connect said additional terminals to the calling-line, whereby a common conversational circuit is 35 established including said telephone-lines.
- 40 27. In a telephone system including telephone-lines, and means at the exchange for connecting them in pairs in individualized
- 45 circuits, the combination with a plurality of 50 lines of a special-service circuit therefor, and means for transmitting distinctive signals over a calling-line to operate said special-service circuit to switch said plurality of lines into a common circuit including the calling-line.
- 50 28. In a telephone-exchange system, a plurality of telephone-lines connecting substations with the exchange, a special-service circuit including mechanism adapted to connect 60 it to certain lines, a calling-substation, a selective switch at the exchange, means at the substation for transmitting distinctive signals to said switch to cause it to connect said line with said special-service circuit and operate said circuit to connect said line and said certain lines into a common circuit.
- 55 29. In a telephone-exchange system, a plurality of telephone-lines connecting substations with the exchange, a special-service circuit including mechanism adapted to connect 65 it to certain lines, a calling-substation, a selective switch at the exchange, means at the substation for transmitting distinctive signals to said switch to cause it to connect said line with said special-service circuit and operate said circuit to connect said line and said certain lines into a common circuit, and means operable from a substation adapted to 70 destroy said common circuit.
- 65 30. In a telephone system, telephone-lines connecting substations with the exchange, selective switches at the exchange for connecting said lines, under substation control, in pairs for conversation, a special-service 75 circuit at the exchange, branches extending from said circuit to said lines, a calling-substation and a calling device thereat adapted to transmit special signals to a selective switch to cause it to connect the line of said substation with said special circuit and unite 80 all of said lines in a common circuit.
- 75 In witness whereof I hereunto subscribe my name this 11th day of April, A. D. 1905.
- 80 ALFRED H. DYSON.
